CIRCUIT BREAKING DEVICE

Edwin S. True, Oak Park, Ill.

Application January 13, 1933, Serial No. 651,539

16 Claims. (Cl. 200—88)

This invention relates to electrical devices generally and is concerned particularly with electrical circuit breaking devices.

The principal object of the invention is to provide a simpler, more compact, and more reliable device of this character than has heretofore been available. This object is attained by employing a novel control arrangement utilizing both electro-magnetic and electro-thermal action.

10 A device of this character has many useful applications in the electrical art. For example, it may serve as a current limiting appliance performing the functions of an overload circuit breaker or fuse. It presents definite advantages over manually set circuit breakers and fuses in that it does not leave the circuit dead after the overloaded condition is corrected. The device may also serve as an interrupter for producing current pulsations of definite frequencies. Other applications will be readily apparent to those skilled in the art.

One of the main features of the present invention is the arrangement whereby the opening and closing of a set of contacts is controlled both electro-magnetically and electro-thermally. This arrangement permits a positive opening movement and clean contact separation thereby minimizing the tendency to arc.

Another feature is the arrangement of the contacts themselves so as to minimize arcing. This arrangement contemplates the use of flexible, multi-leaf contacts wherein the contact leaves are constructed of metal or metallic alloys possessing arc suppressing properties.

Another feature of the invention is the arrangement of the various elements thereof in such manner that the same may be assembled in a compact unit adapted to fit into the ordinary screw base socket commonly used for fuse mounting. This permits the use of the device with existing circuits and equipment without modification or alteration of the same.

The foregoing features and others not specifically mentioned will be discussed in more detail hereinafter in connection with the description of the device and its operation, reference being had to the accompanying drawing comprising Figs. 1 to 4. Fig. 1 is a sectional view of one embodiment of the invention wherein a single set of contacts is provided. Fig. 2 is a sectional view of another embodiment of the invention wherein two sets of contacts are employed. Fig. 3 is an enlarged view showing the contact construction and supporting method employed. Fig. 4 is a circuit diagram of a device constructed according to Fig. 1.

The construction of a preferred embodiment of the invention may be readily seen by reference to Figs. 1, 2, and 4 of the drawing. In these figures, the reference character 1 designates the usual insulating case provided for screw plug type fuses. Outside contact connections to the holder terminal clips are provided by screw 3 and metallic shell 2. A metallic washer 23 serves to connect shell 2 with the thermo-flexible strip 4. Multi-leaf contacts 5 and 7 are of the same general type as the contacts disclosed in applicant's prior Patent No. 1,769,279 granted July 1, 1930. These contacts are rigidly fastened to thermo-flexible strip 4 and bracket 8, respectively, by rivets 22. An armature 6 of magnetic material 15 is also riveted to strip 4 and, if desired, may act as a contact and current carrying leaf. Alternatively, the upper end of this strip may be provided with an insulator for preventing electrical contact with bracket 8 in which case the function 20 will be that of an armature. In either arrangement the armature serves to focus the magnetic flux so as to distort and draw out any arc that may be established across the contacts. The distortion of an arc in a magnetic field is a well 25 known phenomenon, the theory of which need not be discussed in detail here. It is sufficient to note that, in the device comprising the present invention, the circuit opened by contacts 5 and 7 includes the inductive resistance of coil 10 so 30 that there is a relatively large magnetic flux between the elements 6 and 8 immediately following contact separation. The contacts are within this magnetic field and any arc formed between them will be drawn out and extinguished by the 35 magnetic flux. The bracket 8 is made of magnetic material, for example, soft iron or Allegheny metal, and serves both as a current carrying element and as an element of the magnetic circuit 40 of the coil. The bracket is in electrical contact with metallic washer 18, one side of which is bent up as shown to provide a suitable connection with conductor 10. The core 9 is preferably constructed of the same material as bracket 8. Conductor 10 may be of copper or other suitable conducting 45 material, its size depending upon the current carrying capacity desired. The number of turns of conductor wound on core 9 are governed by the inductance desired and by the force to be exerted on armature 6, which are in turn a 50 function of the operating limit desired. The lower end of conductor 10 is connected to a bent up portion of washer 17 which is in electrical contact with screw 3. Bracket 13 is made of the same type of metal as core 9 and serves the double 55

purpose of providing an adjusting bearing for strip 4 and of reinforcing the magnetic path between core 9 and armature 6. Screw 21 controls the adjustment of strip 4 by varying the tension thereof. It will be appreciated that an increase in the tension of strip 4 will increase the speed with which it reacts to the removal of the magnetic attraction from armature 6. Further, the screw 21 mechanically limits the extent to which the strip can move and thereby controls the extent of contact movement. The insulating washers 11 and 14 and bushings 12 and 15 separate the various conducting elements so as to permit the proper circuit connections. The various elements are assembled as a rigid unit and are held together by screws 3 and 20 which extend through insulating end pieces 19 and 24 to core 9.

The thermo-flexible strip 4 controls the opening of contacts 5-7 by flexing in such manner that contact 5 is moved out of engagement with contact 7 which is stationary. Armature 6 is also moved as strip 4 flexes, this movement being opposed by the electro-magnetic force exerted by coil 10 prior to the opening of the contacts. The thermo-flexible strip is preferably composed of two laminae of different metals welded together along one surface. Bi-metallic material of a suitable nature is well known in the art and is readily obtainable commercially. A particularly suitable element is one in which the upper lamina consists of an iron alloy having magnetic properties. The lower lamina in this case will ordinarily consist of an alloy of copper although any suitable metal may be employed. The strip constitutes one of the current carrying elements of the device as shown and is heated by the current flow therethrough. The extent of flexure and the torque exerted by the strip depend jointly on the dimensions thereof and the temperature attained. The temperatures to which predetermined currents will raise the strip are functions of its cross sectional area and effective resistance. By proper proportionment of these factors and by the application of the necessary mechanical tension on the contacts when no current is flowing the device can be made to open a circuit when any predetermined rate of current flow is exceeded. This arrangement permits the use of the device as a current limiting appliance, wherein it automatically opens a circuit in response to an overloaded condition. The opening of the circuit likewise stops the heating of the strip which returns to normal position and closes the contacts. If, upon the reestablishment of the circuit it is found that the overloaded condition persists, the strip will rapidly flex again and reopen the circuit. This cycle of operations will be repeated indefinitely until the overloaded condition is corrected. The intermittent operation above described will cause the flashing of lamps connected in the circuit and will in this manner call attention to the condition of the circuit.

The functions of the electro-magnetic coil arrangement will now be explained. It will be seen that in the particular embodiment of the invention shown, the coil is connected in series with contacts 5-7. The coil may also be connected in parallel with the contacts or may be provided with a plurality of windings with both series and parallel connections. The current flow through the coil will establish a magnetic flux in core 9. Brackets 8 and 13 and strip 4 which are separated from the core by the relatively thin insulators 11 and 14 provide a magnetic path between the core and armature 6. With the coil

energized as it will be whenever there is any current flowing in the circuit with which the device is associated, armature 6 will be attracted to bracket 8 with a definite force. This force opposes the tendency of strip 4 to flex and open the contacts as its temperature rises. In this way it tends to maintain steady contact pressure. Strip 4 is so proportioned that when a predetermined current limit is exceeded, the torque exerted by the strip will exceed the attractive force exerted on armature 6. The contacts accordingly open and stop the current flow through the coil. The magnetic flux is dissipated and armature 6 is no longer attracted to bracket 8. The thermo-flexible strip can now flex to its limit without opposition and in doing this it separates the contacts in such a manner as to greatly reduce the tendency to form an arc and to prevent the maintenance of a destructive arc. The longitudinal magnetic flux through the contacts serves to suppress the tendency to arc during the initial contact opening step and acts as a magnetic blow-out in case an arc is found. Strip 4 cools, of course, with the circuit open, and, after a definite interval, recloses the circuit. In case circuit conditions are still adverse, the cycle of operations above described will be repeated.

Referring now to Fig. 2, the arrangement shown is generally similar to that of Fig. 1 except for the employment of two sets of contacts and the centering of the electro-magnet core. The contacts are provided with separate adjusting means which permits individual regulation as to time and speed of contact separation and also as to operating current limit. Case 31 and shell 32 are the same as the corresponding parts in Fig. 1. Screw 33 takes the place of core 9 and screws 3 and 20 of Fig. 1. This screw is made of the same material as core 9 and serves both as core and one outside contact. Conductor 40 which corresponds to conductor 10 is wound on insulating sleeve 45 through which core 33 extends. The contact assemblies and their supporting brackets are exactly the same as those shown in Figs. 1 and 3. The electrical circuit of this device may be traced from contact 33, bracket 38, contacts 37 and 35, thermo-flexible strips 34 and 58 which, incidentally, may be formed of a single piece drilled to accommodate sleeve 45, contacts 55 and 57, bracket 50, washer 48 and its bent up portion 60, conductor 40, washer 47 and its bent up portion 61, metallic disc 53, to shell 32. While in the present instance the two contacts have been shown connected in series, it will be appreciated that either multiple or series-multiple connection may be used instead when circuit conditions require.

Having described my invention, what I consider new and desire to have protected by Letters Patent will be pointed out in the appended claims.

What is claimed is:

1. In combination, a fixed contact member, a movable contact member comprising a plurality of flexible non-magnetic leaves and a magnetic leaf engaging said fixed contact member, a thermo-flexible element adapted to actuate said movable contact member, and an electromagnet adapted to attract the magnetic leaf of said movable contact member.

2. In combination, a fixed contact member, a movable contact member comprising a plurality of non-magnetic leaves and a magnetic leaf, each of said leaves engaging a different portion of said fixed contact member, a thermo-flexible element

- connected in circuit with said contact members and adapted to exert a definite torque upon the movable contact member, and an electro-magnetic coil adapted to attract said magnetic leaf to counteract the torque exerted by said element.
5. A circuit controlling device comprising an electro-magnet, a pair of contact members, and a thermo-flexible element, wherein said contact members and said element are included in both the electrical and magnetic circuits of said magnet.
10. A circuit controlling device as claimed in claim 3 in which the thermo-flexible element and the electro-magnet apply opposing forces to the contacts.
15. A circuit controlling device as claimed in claim 3 in which arcing across the contacts upon their separation is inhibited by the magnetic field passing through the contact members at the instant of opening.
20. A protective device comprising a fixed contact member, a movable contact member actuated by a thermo-flexible element, a magnetic coil, a magnetic circuit for said coil including the core of said coil, the stationary and movable contact members and the contact supporting structure, and means including said thermo-flexible element acting in opposition to said coil for separating said contacts by a suitable air gap when currents beyond a predetermined value are passed through the device.
25. A circuit breaker comprising a fixed contact, a movable contact actuated by a thermo-element, a magnetic coil, a core, an extension of said core comprising contact support portions, means for separating said contacts by a suitable air gap responsive to a pre-determined current flow, and coating means and including said coil and said support portions for compensating magnetically the contact pressure and movement supplied by the thermo-element.
30. The combination with movable multi-leaf contacts repeatedly and automatically opened and closed by current responsive elements, cooperating electro-magnetic and thermal means for equalizing contact pressure whereby said contacts are held closed below predetermined current values, and means for directing a magnetic flux between the leaves of the contacts upon the opening of the contacts to effect arc suppression.
35. A circuit controlling device comprising an electro-magnet, a thermo-flexible element with its supporting end clamped to the core of said magnet, a set of contacts controlled jointly by said magnet and said element, and an insulating case mounted on the core of said magnet enclosing the magnet, the element and the contacts.
40. A contact device comprising a multi-leaf contact element mounted on a stationary bracket of magnetic material, a multi-leaf contact element mounted on a thermo-flexible element and normally engaging said first element, a second bracket supporting said thermo-flexible element, a bridging member mounted on said thermo-
- flexible element and extending to said first bracket to provide a magnetic path between the element and said first bracket, a coil, a core extending through said coil, and means attaching said brackets to opposite ends of said core.
45. In a circuit controlling device, an electro-magnet, a core for the magnet, a bracket of magnetic material attached to one end of the core, a thermal element attached to the other end of the core, a strip of magnetic material mounted on said element and cooperating with said bracket to complete the magnetic circuit of the magnet, and a pair of co-operating contacts mounted respectively on said bracket and said element so as to lie within the magnetic field extending from said strip to said bracket.
50. A circuit controlling device comprising an electro-magnet, a fixed contact supported on the core of the magnet, a thermo-flexible element attached to the core of said magnet and carrying a contact adapted to engage said fixed contact, a bracket attached to the core of said magnet, and adjusting means attached to said bracket for exerting a variable tension on said element.
55. A circuit controlling device comprising an electro-magnet, a bracket of magnetic material attached to each end of the core of said magnet, each bracket having one end bent to lie substantially parallel with the magnet core, a contact member attached to one bracket, a thermo-flexible element attached to one end of the magnet core and carrying a contact member adapted to engage said first contact member, and a magnetic strip attached to said element to lie substantially parallel to the magnet core and bridging the gap between the two bent ends of said brackets.
60. A circuit breaker comprising an electro-magnet, a thermo-flexible element and a contact member attached to the core of said magnet, a contact member attached to said element and engaging said first contact member when said element is in normal condition, and an armature attached to said element and disposed within the field of said magnet whereby the magnet is enabled to oppose the separation of said contact members due to flexing of said element.
65. A circuit controlling device comprising an electro-magnet, a thermo-flexible element and a contact member attached to the core of said magnet, a contact member on said element engaging said first contact member, and an armature attached to said element and disposed so as to complete the magnetic circuit of said magnet.
70. A circuit controlling device having, in combination, an electro-magnet, a pair of contacts supported at one end of the magnet, a thermal element supported at the other end of the magnet, and a pair of contacts carried by said thermal element and adapted to engage said first contacts to complete respectively, an electrical circuit and a magnetic circuit for said magnet.
